LOCK HASP

Abraham Levine, Elizabeth, N. J., assignor to
Presto Lock Corporation, New York, N. Y., a corporation of New York

Application November 19, 1930, Serial No. 496,626

11 Claims. (Cl. 292—281)

My present invention relates generally to locks and more particularly to locks employed for brief cases and the like and in which a hasp member carried from one part is arranged to engage a locking member carried by another part to secure the parts in associated relation.

One of the objects of my invention is the provision of a new type of hasp structure.

Another object of my invention is the provision of a new manner of stamping a blank so as to provide a hasp.

Another object of my invention is the provision of a hasp having a name plate associated therewith.

15 It is still a further object of my invention to provide a new and improved arrangement in the locking member for holding the plug or bolt thereto in its sliding relation for latching and unlatching purposes.

20 For the attainment of these objects and such other objects as may hereinafter appear or be pointed out, I have illustrated an embodiment of my invention in the drawings wherein—

Figure 1 is a front elevational view of my new 25 lock in position on a brief case;

Figure 2 is a section through the hasp taken on line 2—2 of Figure 1 looking in the direction of the arrow;

Figure 3 is a bottom view of the hasp as seen 30 from below in Figure 2;

Figure 4 is a side elevational view of the hasp before it is attached to the brief case;

Figure 5 is a front elevational view of the hasp of Figure 4 as seen from the left in that 35 figure;

Figure 6 shows the blank from which the hasp of Figures 4 and 5 is formed;

Figure 7 is a front view of the lock;

Figure 8 is a rear view thereof;

40 Figure 9 is a section taken on line 9—9 of Figure 7;

Figure 10 is a section taken on line 10—10 of Figure 9 looking in the direction of the arrows;

Figure 11 is an enlarged fragmentary view of 45 the lock parts during a stage of its assembly; and

Figure 12 shows a stamping such as used for my lock, before assembly thereto.

Upon viewing Figure 1 of the drawings, it will 50 be observed that my invention relates to the type of lock which is provided with a hasp 10 secured as for example to the flap of a brief case and arranged to engage with and lock to a locking member 11, secured to the front fold of the briefcase. The details of the hasp construction

and the manner of its manufacture are shown in Figures 2 to 6 and the details of the locking member and the manner of its assembly are shown in Figures 7 to 12. I will first describe the former.

In Figure 6, I show a blank of sheeted metal cut so as to provide the halves 15 and 16 to be bent into parallelism along lines 17 and 18 to provide the two walls 19 and 20 of the hasp of Figures 4 and 5. To facilitate the bending operation, the blank of Figure 6 may be scored along lines 17 and 18 although this is not necessary as this bending can be done without the scored lines.

A hasp of the character herein referred to is 70 generally provided with a perforated projection to enter an opening in the locking member so as to receive a locking element through the perforation in the hasp projection. This, hitherto, has generally been attained by securing to the hasp a 75 relatively rigid perforated member which projects outwardly from the face of the hasp and which is secured thereto as by a welding or riveting operation. In accordance with my invention as herein disclosed, I attain the same results 80 in a more effective manner by a stamping operation and this I will now describe, in connection with the blank of Figure 6, and the finished hasp of Figures 2, 3, 4, and 5.

The blank of Figure 6 is provided within the 85 general contours of the part 15 with the two parallel cuts 21 and 22. The upper ends of these cuts are connected by the oval shaped cut 23, thus providing two extensions or ears to which reference will be made further on. The cuts 21 90 and 22 extend preferably in the opposite direction into the webbing connecting the two portions 15 and 16 or in other words into the material between the lines 17 and 18. Within the parallel cuts, 21 and 22, and closely adjacent and parallel 95 to the line 17, the part 15 is cut away to provide the elongated opening 25.

I will now describe how either before, during or after the operation of bending the parts 15 and 16 of the blank 6 into substantial parallelism 100 to the hasp of Figure 4, I provide the interlocking element of the hasp by merely a bending operation. Upon viewing Figure 4, it will be observed that the part defined by the cuts 21, 22 and 23 and which part will hereinafter be referred to by the reference character 24, has been doubled back upon itself transversely, and intermediate of the ends, of the side cuts, 21 and 22, so as to give the substantially parallel portions 25' and 26 and to provide in the face 19 of the hasp the 110

elongated opening 27 (see Fig. 5) widened at its upper end, as shown at 28 in this figure. The material within the cut 23 (see Fig. 6) and to which the reference character 29 will be applied hereafter, is bent upwardly at right angles to the parts 25' and 26. Due to the foreshortening of the part 24 (see Fig. 6) by bending upon itself, as shown in Fig. 4, the widened part 29 will be brought out of registry with and below the enlarged opening 28, (see Fig. 5) and will be brought into opposition to the narrower opening 27, and the projections or ears 30 into contact with the inner surface of the wall member 19, and therefore will serve to hold the parts 25 and 26 generally in a position such as shown in Fig. 4 of the drawings. The position of the opening 25, in the part 25', is shown very clearly in Figs. 2 and 3.

The hasp can be secured in position over the edge of the flap of a briefcase or any similar article by any preferred or desired means such as prongs 35. In Fig. 2, I have shown the hasp of Figs. 4 and 5 secured in position about such edge and in this figure, "A" is applied to the leather flap of a briefcase and upon carefully viewing this figure, it will be observed that the member 29 will be locked between the inner surface of the member 19 and the flap of the briefcase so that the elements 25' and 26 which will define the locking element of the hasp will not only be locked in position but will be given considerable rigidity and will serve all purposes of the locking member hitherto employed and yet will have sufficient yieldability so as to provide for any inaccuracies in manufacturing or assembling process or for any warping or distortion of the parts.

I will now describe my arrangement for forming from the part 16 of the blank of Figure 6, the name plate holder to which the reference character 30', has been generally applied in Figure 1. This name plate comprises an upper half 31 and a lower half 32, duplicates of each other but in reversed position to each other. The part 31 comprises a portion of the material bent out of the plane thereof so as to provide the end wall 35' at the left, the top wall 36 and the overhanging front wall or face 37. These walls define a channel which is closed at the left and on the top and which is open at the right and at the bottom for reasons that will be pointed out. The part 32 is similarly provided with an end wall 38 at the left, a wall 39, which, however, here is at the bottom, and a front wall 40, which between them define a passageway which is also closed at the left but open at the right but with respect to the part 32 is also open toward the top. These raised portions 31 and 32 are generally U-shaped with the legs of the U in vertical alignment and spaced slightly apart. Due to the U-shape of the members and to the spacing of the legs, an enlarged exposed opening is provided.

A name plate such as shown at "B" in Figure 1 is inserted at the right so as to bring it below the overhanging walls 37 and 40 of the members 31 and 32, until the left hand end of the name plate strikes the left hand walls, 35 and 38. The name card can be removed by moving it in the opposite direction and in this operation is assisted among other things by the spacing of the legs above referred to.

The name plate holding construction above described is formed from the part 16 of the blank in the manner shown in Figure 6. This blank is cut through along the full lines 45 and

46 in said figure and then is bent upwardly along the dotted lines 47 and 48. The cuts 45 and 46 each comprise two spaced horizontal cuts in horizontal alignment, connected at their adjacent and inner ends by an intermediate U-shaped cut and extending upwardly from the outer end of one of the horizontal cuts, as for example the one at the right, is a vertical cut. The material between cut 45 and the dotted line 47 and between the cut 46, and the dotted line 48, when bent upwardly out of the plane of the part 16 will give the name plate holder the conformation described above.

My preferred process for stamping the blank of Figure 6, then forming therefrom the hasp construction of Figure 4 is as follows:

In the first operation, the blank of Figure 6 is cut out in all respects as shown in Figure 6, except as to the cuts 45 and 46 which are made together with the second or forming operation.

The second step comprises the simultaneous performance of the following: (a) the cuts 45 and 46 are made in the section 16 and the material between each and the lines 47 and 48 respectively is bent up to complete the name plate holder; (b) the parts 24 and 29 in Figure 6 are bent generally as shown in Figure 4, and (c) the securing prongs 35 are bent inwardly at an angle to the blank.

In the third and final operation, the hasp is doubled upon itself and the locking prong made up of the elements 25', 26 and 29 given its final position of Figure 4.

Upon viewing Figure 1 of the drawings, it will be observed that the name plate appears on that face of the hasp which is exposed to view and the locking element of the hasp is at the back thereof as shown in Figure 4. The parts 25' and 26 are so dimensioned and spaced as to be receivable within any of the openings 50 of the lock member 11 to bring the opening 25 in the path of one of the projections 51 carried by a reciprocating bolt 52, (see Figs. 8 and 9). The bolt is mounted for reciprocation within the lock casing 11 and is spring pressed into locking position 120 and is moved into hasp releasing position by operating knob 53 (see Fig. 7), by mechanism which may be of the conventional type and therefore is not shown except as far as it is indicated in Figure 8 in dotted lines.

I will now describe my novel arrangement for holding the locking bolt 52 in position against the inside face of the locking casing 11 so as to permit of its aforementioned reciprocation.

Upon viewing Figs. 11 and 12 of the drawings, it will be observed that the face plate 11 of the locking member, by a stamping operation or the like, has material removed at spaced points thereof as shown at 56 to leave the tongues 57 and 58, which tongues are separated from the body of the material by the side cuts, 59, thus leaving the tongues connected to the material only along the line 60. These tongues, 57 and 58 are then bent upwardly and inwardly at right angles to the face plate as shown in Fig. 11 and in the instant case, three groups of such tongues will be employed. The bolt, 52, is in the form of a bar or sheet of metal also cut out at spaced points as shown at 61, so as to leave the projecting tongues 51 and the cutout portions 62 and 63 on either side of each of said tongues.

In assembling the bolt 52 with the face plate, it will be understood that, where, as in the instant case, three locking positions are to be provided, the face plate will be provided with the three

openings 50 and with the three groups of projecting tongues 57 and 58. The parts are so dimensioned that when the bolt 52 is positioned against the inner face of the face plate 11 the three groups of tongues 57 and 58 will be received each through a cut out portion 62 or 63 of an opening 61 of the bolt, and the side walls of these portions 62 or 63 will be adjacent to and will be guided by the outer faces of the widened parts 57' and 58' of the upstanding fingers 57 and 58. The height of these widened parts is substantially equal to the thickness of the bolt 52. The projecting finger portions 58'' and 57'' can then be bent each outwardly and downwardly to contact with the outer face of the outer surface of the bolt 52 so as to keep the bolt down in contact with the inner face of the face plate 11 and at the same time to permit of the relative reciprocation of the bolt with reference to the face plate. This reciprocation will be limited by the front and back walls defining the opening 60.

It will be understood that the bolt 52 is intended to be locked by suitable locking mechanism indicated in Figure 8, but not shown in detail, as it may be of any well known type suitable for the purpose.

Having thus described my invention and illustrated its use, what I claim as new and desire to secure by Letters Patent is—

1. A hasp for a lock comprising two oppositely disposed walls integrally united at one end and a lock engaging element carried by one wall, said element comprising a section formed integrally with and extending out from one of the walls, said section being doubled back upon itself to provide superimposed parts, and an opening in one of said parts adapted to receive a locking element therethrough.

2. A hasp for a lock comprising two oppositely disposed walls integrally united at one end and a lock engaging element carried by one wall, said element comprising a section formed integrally with and extending out from one of the walls, said section being doubled back upon itself to provide superimposed parts, and an opening in one of said parts adapted to receive a locking element therethrough, and means associated with the other part to secure it in position.

3. A hasp for a lock comprising two oppositely disposed walls joined by an integral connection at one end and a lock engaging element carried by one wall, said element comprising a section formed integrally with and extending out from one of the walls adjacent said integral connection, said section being bent intermediate its ends to provide two superimposed parts, and means in that part adjacent said integral connection adapted to receive a locking means therethrough.

4. A hasp to form part of the locking arrangement of a briefcase or the like, said hasp comprising two oppositely disposed walls joined to each other at one end and a locking element for said hasp carried by one of said walls and comprising two superposed sections joined to each other at one end and positioned generally at right angles to the general plane of the hasp, and an opening formed in the lower of said elements.

5. A hasp to form part of the locking arrangement of a briefcase or the like, said hasp comprising two oppositely disposed walls joined to

each other at one end and a locking element for said hasp carried by one of said walls and comprising two superposed sections joined to each other at one end and positioned generally at right angles to the general plane of the hasp, and means for holding the two sections in position with reference to said wall carrying the locking element.

6. A hasp to form part of the locking arrangement of a briefcase or the like, said hasp comprising two oppositely disposed walls joined to each other at one end and a locking element for said hasp carried by one of said walls and comprising two superposed sections joined to each other at one end and positioned generally at right angles to the general plane of the hasp, and means for holding the two sections in position with reference to said wall, said means comprising a portion carried by one of the sections adapted to overlap a portion of said wall carrying the locking element.

7. The combination with a brief case, of a hasp secured about a free end thereof, an inner wall of the hasp having extended outwardly therefrom a section of the same material and integrally united with the main body of the hasp, said section being integrally associated with the hasp at one end and having its opposite end in sliding engagement with the hasp.

8. In combination with a briefcase, a hasp secured about a free end thereof, the inner wall of the hasp having extended outwardly therefrom a section of the same material and integrally united with the main body of the hasp, said section being integrally associated with the hasp at one end and bent intermediate its ends and having on its opposite end outwardly extending ears in sliding engagement with the hasp.

9. In combination with a briefcase, a hasp secured about a free end thereof, the inner wall of the hasp having extended outwardly therefrom a section of the same material and integrally united with the main body of the hasp, said section being integrally associated with the hasp at one end and bent intermediate its ends and having on its opposite end outwardly extending ears in sliding engagement with the hasp, the ears being received between the inner face of the inner wall of the hasp and the briefcase material.

10. A hasp for a lock made of sheet material and comprising two oppositely disposed walls integrally united at one end and a lock engaging element carried by one wall, said element being integral with and comprising an outwardly projecting section of said wall, said element being the entire said section, thereby leaving an opening in said wall of the contour of the section.

11. A hasp for a lock comprising two oppositely disposed walls integrally united at one end and a lock engaging element carried by one wall, said element comprising a section formed integrally with and extending out from one of the walls, said section being doubled back upon itself to provide superimposed parts and means associated with one of said parts and adapted to cooperate with a locking element for the purpose of holding the hasp in locked relation with the other portions of the lock.

ABRAHAM LEVINE. 145
